MACHINE FOR OPERATING ON SHOE PARTS

Chester W. Greene, Lynn, Mass., assignor to
United Shoe Machinery Corporation, Paterson,
N. J., a corporation of New Jersey

Application April 22, 1935, Serial No. 17,564

21 Claims. (Cl. 12—97)

This invention relates to machines for hot-pressing and shaping shoe upper parts and, in the embodiment shown for the purpose of illustration, comprises a heated form having a transverse curvature similar to but preferably less than that assumed by a lasted shoe upper and a cooperating presser member adapted to press the vamp portion of an unlasted shoe upper against the form with sufficient pressure and for a sufficient time to cause a shape similar to that of the form to be imparted to the shoe upper. The machine is adapted for practicing the method disclosed in Letters Patent of the United States No. 2,015,090, granted September 24, 1935, in the name of Harold L. Sawyer.

An object of the invention is to provide an improved machine for use in shaping a shoe part, for example a vamp, to a desired contour, the shoe part being maintained in that condition under the influence of pressure and heat for a predetermined time and then released.

Features of the invention consist in power-operated means for mechanically operating the form and presser member relatively to each other, thereby to apply pressure to the work, to maintain the pressure for a predetermined time and then to release the pressure. The duration of the predetermined time may be varied. In the illustrated machine, a cam slowly driven by power is connected by a heavy spring to the presser member and, upon starting of the cam in one direction, the presser member is pressed against the form through the spring. After the cam has made part of a revolution its direction of motion is automatically reversed and upon its return to its original position the pressure is relieved and the power disconnected from the cam. The point during the rotation of the cam at which its motion is reversed may be varied and hence the period during which the power is maintained under pressure may be changed to suit varying conditions.

Another feature of the invention consists in an improved presser member comprising a flexible sheet, preferably lined with felt, the side portions of the sheet being connected to members pivoted by links to a rigid lever operated by the aforesaid cam. Movement of the lever toward the form causes the middle portion of the flexible sheet to press upon the form, and the action of the links then forces the side members against the form. A spring is provided to separate the side members when the pressure is relieved.

The illustrative machine is duplex, both sides of the machine being driven from the same source

of power between which and the respective cams on opposite sides of the machine automatically operated reversing mechanism is provided.

These and other features of the invention will appear more fully from the detailed description when read in connection with the accompanying drawings and will be pointed out in the appended claims.

In the drawings,

Fig. 1 is a perspective view of a machine embodying the present invention;

Fig. 2 is a side elevation, partly in section, of the machine;

Fig. 3 is a perspective view, partly broken away, of an illustrative closed shoe upper, the vamp portion of which the machine of the present invention is designed to treat;

Fig. 4 is a transverse section taken through the heated form and presser member illustrating the operation of the presser member;

Fig. 5 is a perspective view of a safety mechanism with which the machine is provided;

Fig. 6 is a perspective view illustrating the gearing connecting the source of power to the mechanism for operating the presser member at each side of the machine;

Fig. 7 is a sectional detail of parts shown in Fig. 6; and

Fig. 8 shows in perspective details of parts shown in Figs. 6 and 7.

The illustrated machine for hot-pressing and shaping the vamp portion of a closed shoe upper for the purpose, for example, of causing thermoplastic cement between the upper and the lining to be activated and to give the upper a preliminary shape similar to that which it will have to assume in the completed shoe is provided with a frame 10 upon which is a table 12. On the table 12 are mounted two heated forms 14, 16, each of which contains a heating element 18 (Fig. 4) connected by suitable conductors 20 (Fig. 1) to a junction box 22 to which electric energy is supplied, a switch 24 being provided to control the current supplied to the heating elements 18. To protect the operator's hands from coming into contact with the heated forms 14, 16, an insulated shield 26 is provided in front of each of the two forms. The top portion of each form 14, 16 is substantially cylindrical in shape, the preferred curvature being somewhat less than that which the shoe upper will assume after it has been drawn over a last. The lower portions of the forms flare outwardly and downwardly giving the form the general shape of a truncated wedge.

The construction of presser members 30, 32, with one of which each form is provided, is best shown in Fig. 4, where 34 indicates an outer shell of thin steel or the like, side portions or flanges 5 of which are secured by screws 36 to side presser members 38, 40. Inside the shell 34 is a thick layer 42 of resilient material, for example soft rubber, and inside the rubber is a layer 44 of felt. The felt layer 44 and rubber layer 42 are 10 preferably held in place by metallic clips secured to the members 38, 40 by screws 36 and having their inner edges bent up against the felt layer. In order to provide a wearing surface to 15 protect the felt, it is preferable to line the presser member with fabric, the lower edges of which may be tied at 41 (Fig. 4) to the projecting ends of the screws 36 and the upper portion of which may be held in place by strips 46 (Figs. 1 and 2) of adhesive tape or the like. The side presser 20 member 38 is connected to one arm 48 of a lever the other arm 50 of which carries a stop screw 52 adapted to engage a head 54 to one side of which the lever 48, 50 is pivoted at 56. On the other side of the head a similar lever 58, 60 is 25 pivoted at 62, the upper arms 50, 60 of the levers being connected by a tension spring 64 which, when allowed to act, swings the levers 48, 50 and 58, 60 in opposite directions, thus separating the side pressers 38, 40 and causing the presser 30 member 30 to open. It will be obvious that when the head 54 is raised the spring 64 will act to separate the side pressers 38, 40, and the arms 48, 58 will extend downwardly with only a slight inclination toward each other.

35 When work which may consist, as shown in Fig. 3, of a closed shoe upper having a vamp A, a quarter B and a lining C, is placed over the form 14 and the head 54 moved downwardly, the curved center portion of the presser member 30 40 will first engage the work in the region of the curved top of the form and continued downward movement of the head 54 will cause the spring 64 to be stretched and the side pressers 38, 40 to be moved toward each other to apply 45 pressure to the side portions of the presser member 30. Thus, the work will be wrapped about the form and held tightly to the form while receiving heat therefrom to shape and set it. The upper front portion of the presser 50 member 30 may be cut away at 66 so as not to apply pressure to the upper part of the throat portion of the upper, and usually there is no advantage in applying pressure to the tip portion of the vamp and lining, which layers must 55 subsequently be separated to receive a toe box. Hence, the cooperating portions of the form 14 and the presser member 30 do not extend beyond the tip line of the vamp.

60 It will be understood, of course, that the presser member 32 which cooperates with the form 16 has a construction and mounting identical with that described for the form 14 and presser member 30 and, in fact, that the half of the machine at the right of a central vertical plane extending 65 from front to rear of the machine is duplicated on the other side of that plane, the parts where necessary being made right and left to give the machine as a whole substantial bilateral symmetry with respect to said plane. Particular attention will continue to be paid in the description to the right-hand side of the machine, it being understood that the two sides are operated alternately, receiving power from the same source which, as shown in Fig. 2, may be an electric motor 70 mounted on the rear portion of

the machine frame and connected by a belt 72 to a pulley 74 (Figs. 2 and 6) fixed to a shaft 76 on which is a pinion 78 which meshes with a large gear 80 fixed to a counter shaft 82. On the counter shaft 82 is loosely mounted a large 5 gear 84 similar to the gear 80. A long pinion 86 mounted on a shaft 88 having bearings in the frame has one end meshing with the gear 84 and the other end meshing with a pinion 90 similar to the pinion 78 and fixed on the same 10 shaft 76. The long pinion 86 serves, of course, as a reversing gear so that the large gear 84 will be rotated on its shaft in one direction and the gear 80 and its shaft will be driven in the opposite direction. Loosely mounted on the shaft 15 82 are two clutch sleeves 92 and 94, a detail of one of which is shown in Fig. 8. The sleeves 92 and 94, which of course are freely slideable longitudinally of the shaft 82, are provided on each of their ends with clutch teeth 96 which, 20 in the case of the sleeve 94, cooperate at one end with clutch teeth 98 carried by the gear 80 and at the other end with similar clutch teeth carried by the gear 84. Similarly, the teeth on the clutch sleeve 92 cooperate at one end with teeth 25 carried by the gear 84 and at the other end with teeth carried by a member 100 fixed to the shaft 82 and, of course, driven in the same direction as the gear 80. It will be seen that each sleeve has a neutral position in which it will be at rest 30 and that each, when moved to the right, will be driven in one direction and, when moved to the left, will be driven in the opposite direction.

In order to lessen the shock of engagement of the teeth 96 on the opposite ends of the sleeve 35 members 92 and 94 with the cooperating driven clutch teeth 98 with which they engage, the construction illustrated in Fig. 8 in connection with the gear 80 is provided. On the inner face of the gear 80 there are six lugs 102 integral with 40 the gear. Mounted on the hub portion 104 of the gear 80 is a spider member 106 which has a number of vanes 108 corresponding to the number of lugs 102, each vane 108 resting against the rear face, considering the direction of drive, of 45 one of the lugs 102. Between each vane 108 and the next lug 102 at the rear of it is a spring 110. The teeth 98 with which the teeth 96 engage are formed on the spider 106 and project inwardly at the same distance from the axis of the shaft 82 as 50 the teeth 96 so that when, for example, the sleeve 94 is moved toward the right in Fig. 6 and the teeth 96 engage the teeth 98 of the spider 106 carried by the gear 80 which is being driven in the direction indicated by the arrows in Figs. 6 55 and 8, the spider will yield slightly against the springs 110 and the shock of engagement will be taken up. A cover ring 112 (Fig. 8) having an annular flange 114 is fitted over the lugs 102 and is secured in place by three screws threaded 60 into the alternate lugs 102. The annular flange 114 prevents axial displacement of the vanes 108 on the spider. A spider 106 of similar construction is provided on each face of the gear 84 and on the member 100. Collars 116, one on each 65 side of the gear 84, help to hold the spiders in place and prevent movement of the gear 84 longitudinally of the shaft. Similar collars 118 are provided to prevent displacement of the spider 106 in the gear 80 and in the member 100. The 70 clutch sleeves 92, 94 are each provided with pinion teeth 120 which, in the case of the sleeve 92, mesh with the teeth of a large gear 122 (Fig. 2) to which is secured a pinion 124 which meshes with a large gear 126 in the outer face of which 75

a cam track 128 is formed. It will be understood that the sleeve 94 is connected by similar gearing to a similar cam 129 (Fig. 1) for operating the left-hand side of the machine, said cam being arranged to face in the same direction. Engaging the cam track 128 is a roll 130 mounted on a lever 132 pivoted at 134 to the machine frame at its rear end and at its front end being connected by a link 136 to an arm 138 of an angle lever 140 pivoted at 140 to the machine frame. The other arm 142 of the angle lever is pivoted to the lower end of a rod 144 having a reduced upper end portion 146 that passes through a block 148, through a washer-like collar 150, through a coil spring 152, through a washer 154, and has a nut 156 threaded on its upper end. The block 148 has chamfered corners and normally rests against a nut 158 threaded on the larger portion of the rod 144 and the tension of the spring 152 may be adjusted by turning the nut 156. The spring 152 may be enclosed by a sleeve member fixed to the washer 150 and in which the washer 154 is adapted to slide when the spring is compressed. The block 148 is pivoted between transverse webs 160 connecting the two parts 162, 164 of a double lever pivoted at its rear end on a shaft 166 and integrally connected at its front end to the head 154. The block 148 has recesses in its opposite sides which are engaged by pins 157, one of which is shown in Fig. 1, the pins being held by set screws in holes extending transversely of the lever 162, 164 at right angles to its length.

It will be seen from Fig. 2 that the cam track 128 starts at a point about half way of the radius 35 of the cam, extends toward the periphery and then extends concentrically about the greater portion of the circumference of the cam. Therefore, when the gear 126 is rotated in the direction of the arrow the cam roll 130 will be moved upwardly, operating the lever 132 to push upwardly on the link 136 which will rotate the angle lever 138, 142 in a clockwise direction, pull downwardly on the rod 144 and move the head 54 and its presser member 30 downwardly, causing the presser member to engage the work placed upon the form 14. When the center portion of the presser member 30 is arrested by the form, the side pressers 38, 40 will be pressed inwardly and when the opposition of the form to their further inward movement becomes great enough the spring 152 will be compressed and thus all portions of the work will be held firmly against the heated form 14. Of course this action of the presser member occurs while the roll 130 is passing from the inner portion of the cam track to the peripheral portion, and the pressure may be maintained during substantially a complete rotation of the cam gear 126 and during its reverse movement until the roll 130 again enters the inner portion of the cam track, whereupon the pressure will be relieved and the presser raised away from the work.

The means for controlling the movement of the clutch sleeve 92 toward the left (Fig. 6), then to the right and then to the neutral position shown, first to drive the cam gear 126 in a clockwise direction (Fig. 2), then in the opposite direction and then to stop it, will now be described. The clutch sleeve 92 is provided with a groove 168 which is engaged by a pin or roll 170 mounted on an arm 172 (Fig. 6) of an angle lever pivoted on a pin 174 secured to an arm 176 projecting from the machine frame. The other arm 178 of the angle lever is pivoted to a rod 180. It will be seen that a push on the rod will throw the

clutch sleeve 92 into engagement with the teeth 98 on the member 100, thus causing the cam gear 126 to be driven in a clockwise direction, as indicated in Fig. 6, and that a pull on the rod will cause the other end of the clutch sleeve to engage the teeth 98 on the gear 84 which are being driven in the opposite direction, thus causing the direction of motion of the cam gear 126 to be reversed. The forward portion of the rod 180 is enlarged and slotted at 182 (Fig. 2), the slot being engaged by the central pivot 183 of a toggle comprising a link 184 pivoted to the outer end of the shaft upon which the gear 126 is mounted and a link 186 pivoted to a lever 188, which lever is fulcrumed at 190 and is urged upwardly by tension springs 192 the lower ends of which are connected to the lever between its ends and the upper ends of which are secured to a pin on the machine frame 10. Of course, if desired, a single spring of suitable strength 20 may be used. The forward end of the rod 180 is connected by a link 194 to the lower arm 196 of a lever pivoted between its ends at 198 to the machine frame and having at the upper end of its other arm 200 a transverse projection 202 25 which normally engages the thin forward end 204 of a latch member 206 pivoted at 208 to the machine frame and having its inner end normally held down by a spring 210 against a pin 212 on the frame. The end 204 of the latch member 30 rests against the transverse projection 202, thus preventing forward movement of the arm 200 of the lever 196, 200. While the lever 196, 200 is thus prevented from moving in a counterclockwise direction, the clutch sleeve 92 is in neutral 35 position, as shown in Figs. 6 and 7, and the right-hand side of the machine is at rest. The tension of the springs 192, however, is tending by its upward pull on the lever 198 to break further the toggle 184, 186 and cause the pivot 40 183 to push rearwardly on the rod 180. The forward end of the latch member 206 is connected by a rod 214 to a treadle 216 pivoted at 218 to the machine frame depression of which will lift the thin forward end 204 above the transverse projection 202 and allow the lever 196, 200 to move in a counterclockwise direction under the influence of the springs 192 and the rod to be pushed rearwardly, causing the clutch sleeve 92 to be shifted toward the left in Fig. 7 into 45 clutching engagement with the member 100 which is being driven by the motor 70 in a clockwise direction, and which then, through the reducing gears 122, 124, slowly drives the cam gear 126 in a clockwise direction, causing the presser member 30 to be pressed on the work applied to the form 14, as has been described.

On the hub portion of the cam gear 126 is secured a disk 220 (Figs. 1 and 2) in which is a series of holes 222 and on which is a fixed lug 224 through which is threaded an adjustable contact screw 226. A screw 228 may be placed in any one of the holes 222 and, when placed as shown in Fig. 2, permits about two thirds of a revolution of the cam gear 126 before it engages 60 the link 184 of the toggle 184, 186. When it does so engage the toggle, the toggle is first straightened against the tension of the springs 192 and, when the toggle is moved past its center or straight position, the springs 192 react to force 65 the pin 183 against the forward end of the slot 182, causing the rod 180 to be pulled forward and the clutch sleeve 92 to be shifted to the right in Fig. 7 out of engagement with the teeth on the member 100 and into clutching engagement with 70 75

the clutch teeth on the gear 84 which, of course, is moving in the opposite direction to the member 100. During this action the lever 196, 200 is moved in a clockwise direction, allowing the latch 5 member to be drawn by its spring 210 into the position shown in Fig. 2 with its thin forward end 204 in alignment with the lateral projection 202. The cam gear 126 is now moving in a counterclockwise direction and, when the contact screw 226 engages the link 184 of the toggle, the toggle is moved from its forwardly bent position first into a straight position and then past the center, whereupon the springs 192 push the rod 180 rearwardly; but since counterclockwise 10 movement of the lever 196, 200 is prevented by the latch member 204, they can only move the clutch sleeve to the left (Fig. 6) far enough to disengage the clutch teeth from the gear 84, whereupon the cam gear 126 comes to rest in the 15 position shown in Fig. 2, where of course the pressure of the presser member 30 has been released.

When the treadle 216 is operated to release the latch 204 from the lateral projection 202 of the 20 lever arm 200, it is desirable to provide yielding means for holding the lever arm in its forward position with the clutch sleeve 92 in clutching engagement with the member 100 and prevent accidental movement thereof out of such clutching 25 engagement. For this purpose an arm 230 is pivoted at 232 to the machine frame and a detent 234 is pivoted to the arm at 236 so that it can swing rearwardly but is prevented from swinging forwardly by a ledge 238 on the arm. 30 A link 240 is pivoted to the arm 230 above the detent and has its lower end portion pressed against the detent 234 by a spring 242. As shown in Fig. 2, the flat lower end of the detent rests against a flat top portion 244 of the arm 200 and when that arm is released by the latch 204 35 and moves forwardly the detent drops over the rearward face of the portion 244 to prevent unintended forward movement of the arm 200. When, however, the lever arm 200 is forced in a clockwise direction, the detent swings rearwardly 40 against the tension of the spring 242 until it slips off the rear edge of the portion 244 and re-assumes the position shown in Fig. 2.

In order to prevent undesired movement of 45 the gearing due to its momentum after the clutch sleeve 92 is moved to neutral position, a brake is provided which comprises a band 246 secured (Fig. 6) to the lower end of a square bar 248 mounted for longitudinal movement in the frame 50 and having at its upper end a split clamp 250 to limit its downward movement. The band 246 passes about a drum 252 formed on the gear 122 and has its other end secured to a pin 254 on an arm 256 extending downwardly and rearwardly 55 from the lever 132. When the lever 132 is moved downwardly by the cam 128, the arm 256 thereon moves rearwardly in a direction to tighten the band 246 upon the drum 252, thus quickly bringing the moving parts to rest.

60 A manually operable pressure-releasing lever 260 is provided by movement of which forwardly the operator may release the pressure of either or both of the presser members. As best shown in Fig. 5, which represents the mechanism at 65 the left-hand side of the machine, the pivot 166 of the double lever 162, 164 is carried by a link member 262 the ends of which are guided for vertical movement in slots 264 formed in up-standing portions of a bracket 266 bolted to the 70 table 12. Below the member 262 is a horizontal

shaft 268 journaled in the bracket 266 and having thereon a lower link member or yoke 270 the arms 272, 274 of which are pivoted to a downwardly extending portion 276 of the member 162 by a pin extending through them and through the 5 portion 276, the pin being secured therein by a set screw 278. It will be seen that the yoke 270 and the member 262 thus form a toggle which is normally straight and is prevented from being broken in a rearward direction by interengaging 10 surfaces at 280 formed respectively on the member 262 and on the arm 272. The toggle may, however, be broken in a forward direction by operation of the lever 260 which is pivoted at its lower end on the shaft 268 and has interengaging connections with a collar 282 fixed to the shaft 268 which, in turn, is fixed to the yoke 270. The forward movement of the lever therefore will break the toggle 270, 262 forwardly and hence move downwardly the rear ends of the double 20 lever 162, 164 so that, if the head 54 thereon is in pressing position, it will move upwardly and the pressure be relieved. The right-hand side of the machine is provided with a toggle mechanism similar to that described and connected in a similar manner to the same lever 260 so that if either one or both of the presser members is in pressing 25 position forward movement of the lever 260 will release either one or both. The lever 260 is maintained in its rearward position with a stop screw 30 284 in contact with a shelf 286 mounted on the brackets 266 by means of a spring 288 connected at one end to a lever above its pivot 268 and at the other end to a pin on the lower side of the shelf 286. 35

A junction box 290 for the motor is mounted on the shelf 286 and is provided with a motor starting switch 292.

Having thus described my invention, what I claim as new and desire to secure by Letters Patent of the United States is:

1. In a machine for pressing parts of shoe uppers together, the combination of a form, a presser member, a cam for relatively actuating the form and presser member to press the work between them, reversing mechanism for rotating the cam first in one direction to apply pressure and then in the opposite direction to release it, and toggle means actuated by the cam for operating said reversing mechanism. 45

2. In a machine for pressing shoe parts together, the combination of a form, a presser member, a rotary cam, connections therefrom for relatively actuating the form and presser member to press the work between them, power-operated means for rotating the cam first in one direction and then in the other, and means actuated by rotation of the cam for causing rotation of the cam to be reversed. 55

3. In a machine for pressing shoe parts together, the combination of a form, a presser member, means for relatively actuating the form and presser member to press the work between them comprising a cam movable in one direction to apply pressure and in the opposite direction to release it, power-operated means for rotating the cam first in one direction and then in the other, and means actuated by rotation of the cam for determining the point in its rotation when its motion will be reversed. 60

4. In a machine for pressing shoe parts together, the combination of a form, a presser member, a rotary cam for relatively actuating the form and presser member to press the work be- 70 75

tween them, power-operated means for rotating the cam first in one direction to apply pressure and then in the opposite direction to release it, and means for varying the interval between the 5 application of pressure and the release of pressure.

5. In a machine for pressing shoe parts together, the combination of a form, a presser member, a rotary cam for relatively actuating the 10 form and presser member to press the work between them, power-operated means for giving the cam a partial rotation first in one direction to apply pressure and then in the opposite direction to release it, a pin on the cam, a bent toggle actuated by the pin to straighten the toggle, and means operated by the toggle for reversing the 15 direction of motion of the cam.

6. In a machine for pressing shoe parts together, the combination of a form, a presser member, a rotary cam, connections therefrom for relatively actuating the form and presser member to press the work between them, power-operated means for rotating the cam first in one direction and then in the other, a toggle arranged to be 20 broken in either of two directions to control the direction of rotation of the cam, and means carried by the cam for breaking the toggle first in one direction and then in the other.

7. In a machine for pressing shoe parts together, the combination of a form, a presser member, a rotary cam, connections therefrom for relatively actuating the form and presser member to press the work between them, power-operated means for rotating the cam first in one direction and then in the other, a toggle arranged to be 25 broken in either of two directions to control the direction of rotation of the cam, means carried by the cam for breaking the toggle first in one direction and then in the other, and means for preventing the second breaking of the toggle from being effective to reverse the cam.

8. In a machine for pressing shoe parts together, the combination of a form, a presser member, a rotary cam for relatively actuating the form and presser member to press the work between them, power-operated means for giving the cam a partial rotation first in one direction to apply pressure and then in the opposite direction to release it, a pin on the cam, a toggle held in bent condition by yielding means and actuated by the pin to straighten the toggle and to carry it beyond its straight position, and means operated by breaking of the toggle in the 30 opposite direction for reversing the direction of motion of the cam.

9. In a machine for pressing shoe parts together, the combination of a form, a presser member, a rotary cam for relatively actuating the form and presser member to press the work between them, reversing mechanism for rotating the cam in either direction and having a neutral position to stop the cam, a toggle capable of being broken in either direction, yielding means arranged to cause the toggle to break in either direction when 35 its joint is moved beyond the straight position, means connecting the joint of the toggle to the reversing mechanism, and means on the cam for actuating the toggle to reverse said mechanism and thereafter to straighten the toggle to set the reversing mechanism in neutral position to stop the cam.

10. In a machine for shaping shoe parts, a convex form, a presser member movable relatively to the form, a cam for operating the presser member, reversing mechanism for driving the cam in 40

either direction, a toggle connected to the reversing mechanism and so arranged that when the toggle is broken in one direction the cam will be driven in one direction and when the toggle is broken in the other direction the cam will be 5 oppositely driven, means tending to break the toggle, and means operated by the cam for causing the toggle to break first in one direction and then in the other.

11. In a machine for shaping shoe parts, a convex form, a presser member movable relatively to the form, a cam for operating the presser member, reversing mechanism for driving the cam in either direction, a toggle connected to the reversing mechanism and so arranged that when 10 the toggle is broken in one direction the cam will be driven in one direction and when the toggle is broken in the other direction the cam will be oppositely driven and when the toggle is nearly straight the cam will not be driven, means on the 15 cam for straightening the toggle and for permitting it to break in the other direction to reverse the cam, other means on the cam to straighten the toggle to stop the cam, and manually releasable means for preventing breaking of the toggle in 20 the first direction to start the cam.

12. In a machine for pressing shoe parts together, the combination of a form, a presser member, a rotary cam for relatively actuating the form and presser member to press the work between them, reversing mechanism for rotating the cam in either direction and having a neutral position to stop the cam, a toggle capable of being broken in either direction, yielding means arranged to cause the toggle to break in either direction when its joint is moved beyond the straight position, means connecting the joint of the toggle to the reversing mechanism, means on the cam for actuating the toggle to reverse said mechanism and thereafter to straighten the toggle to set the reversing mechanism in neutral position to stop the cam, means including a latch 30 to hold the toggle nearly straight to maintain the reversing mechanism in neutral position, and manually operated means to release the latch. 35

13. In a machine for pressing shoe upper parts, a heated form, a presser member cooperating with the form, a lever connected to the presser member at one end, power-operated means for actuating the lever to bring the form and presser member together, and manually operated means connected with said lever for releasing the power-applied pressure. 40

14. In a machine for pressing shoe upper parts, a form, a presser member cooperating with the form, a lever connected to the presser member at one end, a normally fixed pivot for the opposite end of the lever, power-operated means connected to the lever between its ends for actuating it, and manually operated means for lowering the rear 50 end of the lever to release the pressure of the presser member comprising a toggle connected to the rear end of the lever. 60

15. In a machine for pressing shoe upper parts, a form, a presser member cooperating with the form, a lever connected to the presser member at one end, a normally fixed pivot for the opposite end of the lever, power-operated means connected to the lever between its ends for actuating it, a toggle connected to the pivot of the lever arranged to be under compression when the power pressure is applied, and manually operated means for breaking the toggle to release the pressure. 65

16. In a machine for pressing shoe upper parts, a pair of forms, presser members cooperating with 70

75

- the forms, levers each connected to a presser member at one end, normally fixed pivots for the opposite ends of the levers, power-operated means connected to each lever between its ends for actuating it, a toggle connected to the pivot of each lever arranged to be under compression when the power pressure is applied, and manually operated means for breaking both toggles to release the pressure on either or both toggles.
17. In a machine for pressing shoe parts, a convex form, a head movable relatively to the form, levers pivoted between their ends to said head, side pressers pivoted to the lower ends of the levers, a flexible pressing member extending over the form and connected to the side pressers, a tension spring connecting the upper ends of the levers to separate the pressing members, and means for operating the head to wrap the flexible presser member about the form and apply said pressers to the sides of the form in opposition to said spring.
18. In a machine for pressing shoe parts, a convex form, a head movable relatively to the form, levers pivoted between their ends to said head, side pressers pivoted to the lower ends of the levers, the lower arms of said levers being inclined inwardly toward the form and acting as links when the head is depressed to force the presser members against the sides of the form, and means for operating the head to cause the presser members to be pressed upon the form.
19. In a machine for shaping shoe parts, a form, a presser member movable relatively to the form, a cam for operating the presser member, reversing mechanism for driving the cam in either direction, a toggle connected to the reversing mechanism and so arranged that when the toggle is broken rearwardly the cam will be driven in a direction to apply pressure and when the toggle is broken forwardly the cam will be driven in a direction to release pressure, means tending to break the toggle when the toggle is moved beyond its center in either direction, means operated by the cam for causing the toggle to break first for-

wardly and then rearwardly, means for preventing rearward breaking of the toggle substantially beyond its straight position to cause the cam to stop, and means for releasing the toggle to permit it to break rearwardly to start the cam.

20. In a machine for shaping shoe parts, a form, a presser member movable relatively to the form, a cam for operating the presser member, reversing mechanism for driving the cam in either direction, a toggle connected to the reversing mechanism and so arranged that when the toggle is broken in a rearward direction the cam will be driven in a direction to apply pressure, when the toggle is broken in a forward direction the cam will be positively driven to release pressure and when the toggle is nearly straight the cam will not be driven, means on the cam for straightening the toggle and permitting it to break in the forward direction to reverse the cam, other means on the cam to straighten the toggle to disconnect the cam from the reversing mechanism, and a brake band operated by the cam for arresting motion of the cam.

21. In a machine for shaping shoe parts, a form, a presser member movable relatively to the form, a cam for operating the presser member, reversing mechanism for driving the cam in either direction, a toggle connected to the reversing mechanism and so arranged that when the toggle is broken in a rearward direction the cam will be driven in a direction to apply pressure, when the toggle is broken in a forward direction the cam will be positively driven to release pressure and when the toggle is nearly straight the cam will not be driven, means on the cam for straightening the toggle and permitting it to break in the forward direction to reverse the cam, other means on the cam to straighten the toggle to disconnect the cam from the reversing mechanism, a latch for preventing breaking of the toggle in the rearward direction to start the cam, and a treadle for releasing the latch.

CHESTER W. GREENE.
